(57) **CLAIM**

The ornamental design for cookware, as shown and described.

DESCRIPTION

This application is related to co-pending application Ser. Nos. 14/337,112; 29/497,079; and 29/497,080, which are incorporated by reference herein.

FIG. 1 is a top, left and rear perspective view of the first embodiment of cookware showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a cross-sectional view taken along line 8-8 of FIG. 2;

FIG. 9 is a top, left and rear perspective view of the second embodiment of cookware showing our new design;

FIG. 10 is a top plan view thereof;

FIG. 11 is a bottom plan view thereof;

FIG. 12 is a right side elevation view thereof;

FIG. 13 is a left side elevation view thereof;

FIG. 14 is a front elevation view thereof;

FIG. 15 is a rear elevation view thereof;

FIG. 16 is a cross-sectional view taken along line 16-16 of FIG. 10;

FIG. 17 is a top, left and rear perspective view of the third embodiment of cookware showing our new design;

FIG. 18 is a top plan view thereof;

FIG. 19 is a bottom plan view thereof;

FIG. 20 is a right side elevation view thereof;

FIG. 21 is a left side elevation view thereof;

FIG. 22 is a front elevation view thereof;

FIG. 23 is a rear elevation view thereof;

FIG. 24 is a cross-sectional view taken along line 24-24 of FIG. 18;

FIG. 25 is a top, left and rear perspective view of the fourth embodiment of cookware showing our new design;

FIG. 26 is a top plan view thereof;

FIG. 27 is a bottom plan view thereof;

FIG. 28 is a right side elevation view thereof;

FIG. 29 is a left side elevation view thereof;

FIG. 30 is a rear elevation view thereof;

FIG. 31 is a front elevation view thereof; and,

FIG. 32 is a cross-sectional view taken along line 32-32 of FIG. 26.
